FUSE CONSTRUCTION

Alwin G. Steinmayer, Milwaukee, Wis., assignor
to Line Material Company, South Milwaukee,
Wis., a corporation of Delaware

Application May 2, 1938, Serial No. 205,487

18 Claims. (CL. 269—117)

This invention relates to a fuse construction. Objects of this invention are to provide a simple fuse construction which may be used in any capacity but which is eminently suitable as a fuse construction for association with a transformer or other electrical device.

This invention is intended to provide a fuse construction which is particularly useful on a single bushing transformer as these transformers have come into quite general use for rural service. These transformers are provided with only one primary bushing, the other side of the primary winding being solidly grounded to the transformer case.

Objects of this invention are to provide a fuse construction which is carried or supported from the transformer casing, which is so arranged that the discharged gases are directed away from the casing and do not contact with the casing, in which such discharged gases are so directed that they do not endanger a lineman even when he is refusing the transformer and the overload still exists, and which is so made that the fuse may swing in a horizontal plane above the top of the transformer casing.

Further objects are to provide a fuse construction in which the transformer bushing is not subjected to the stresses due to supporting and mounting the fuse tube, in which the fuse is so made that it may be readily removed during refusing without danger to the lineman, in which means are provided for mechanically assisting in withdrawing any unburned portion of the fuse link or leader, in which any remaining unburned portion of the fuse leader is kept away from the live terminal, and in which the invention in one form may provide means for mechanically releasing the extracted remaining unburned portion of the fuse link so that it may be dropped or thrown from the device.

Further objects are to provide a fuse construction for a single bushing transformer in which surge protection is afforded by means of a spark gap which is so connected that after the fuse blows, the transformer is separated from the line but any surges that may occur are taken care of by the spark gap.

Further objects are to provide a construction such that when the fuse blows, a clear indication is given so that the lineman may readily ascertain whether the fuse is intact or whether it needs refusing.

Embodiments of the invention are shown in the accompanying drawings, in which:

Figure 1 is a top view of a transformer equipped with one form of the invention.

Figure 2 is a side elevation of the structure shown in Figure 1.

5 Figure 3 is an enlarged fragmentary view corresponding to Figure 1 with parts in section.

Figure 4 is a view corresponding to Figure 3 showing a modified form of the invention.

Figures 5, 6 and 7 are views of further modified forms.

Referring to Figures 1, 2 and 3, it will be seen that a transformer casing has been indicated by the reference character 1 and is provided with a top or cover 2. The casing and cover are 15 usually made of metal, though obviously other materials could be used provided a ground connection were furnished for the lower member of the spark gap hereinafter described.

The transformer is provided with a bushing 3 20 which carries the upper terminal 4 for the primary. A line receiving terminal 5 is also carried by an insulator 6. One side of the primary, not shown, is connected to the terminal 4 and the other side is grounded within the casing in the usual manner for a single bushing transformer.

The terminal 5 is provided with a connecting portion 7 projecting upwardly therefrom to which the line wire, not shown, may be connected in any suitable manner as by means of the connector 8. The terminal 5 is also provided with an outwardly projecting arm 9 which carries an adjustable upper electrode 10 forming one portion of the spark gap, the lower electrode 11 of which is carried by the cover 2 of the transformer.

35 The fuse comprises an insulating tube 12, one end of which is screwed into a body portion or fuse terminal member 13 which has an aperture therethrough closed by a screw cap 14 in the usual manner and clamping the button of the fuse link 15 in the usual manner. The fuse tube terminal 13 is secured to the line terminal 5 in any suitable manner. For example, it may be provided with the clamping member consisting of a rigid, substantially U-shaped portion 40 16 integral with the member 13 and receiving the screw 17, such screw having a manipulating eyelet 18 at the outer end and having a notched head 19 at its inner end to clamp rigidly against the upstanding portion 7 of the terminal 5 so as to allow the ready removal of the fuse tube therefrom. The construction of the clamping member is very similar to a hot line clamp, though other forms may be used provided they 45 removably support the fuse tube from the line terminal 5.

50 55

The terminal 4 of the transformer carries an outwardly projecting arm 29 which is provided with a recess 21 flaring towards the outer end. At its outer end it is provided with a laterally offset portion 22 which is provided with a pivot pin 23. A rocking arm or fuse extracting and clamping arm 24 is provided with a slot 25 formed in an inwardly projecting lug thereof and receiving the pivot pin 23.

A spring 26 extends between the outwardly projecting portion of the lever 24 and the member 20 and is housed within the recess 21. The member 24 is provided with a thumb manipulating ear or foot 27 at its outer end and with a channel terminal portion 28 at its inner end adjacent the fuse tube 12 and adapted to receive within such channel portion the leader of the fuse link 15. The fuse link clamping and extracting lever 24 is provided with a boss or projecting portion 29, and the member 20 is provided with a similar projecting portion 30 between which the leader of the fuse link is clamped. Preferably these projecting bosses 29 and 30 are staggered or set one in front of the other, as shown most clearly in Figure 3.

When the fuse blows, the gases and metallic vapors are projected in a horizontal plane outwardly away from the transformer casing. As soon as the fuse link is ruptured, it is expelled by the generated gases but also it is mechanically quickly withdrawn by means of the spring urged lever 24. It is to be noted that as the lever 24 rocks in a counterclockwise direction, as viewed in Figure 3, that the outward pull of the lever is at first substantially in line with the fuse tube and consequently very little flexing of the leader of the fuse link is required. Thus a stiffer leader could be used if desired. Also during the first portion of the stroke of the lever 24, the fuse link is still gripped between the bosses 29 and 30, but as the lever 24 continues its rocking motion, the fuse link is freed and is thrown or dropped from the device.

This mechanical withdrawing of any unburned portion of the fuse link materially assists in the quick extinguishing of the arc within the fuse tube.

It is intended that means, not shown, be provided whereby the terminal 5 may be disconnected from the high tension line. For example, in accordance with a very common practice, the connecting wire from the terminal 5 may be provided with a hot line clamp of well known construction and not shown on the drawings, so that it may be detached from the line prior to refusing of the device. The fuse tube is removed from the terminal 5 by releasing the clamping screw 17, see Figure 3, and is refused. Thereafter it is replaced and the screw 17 tightened. The operator then presses the foot or ear 27 of the lever 24 outwardly with his thumb and inserts the leader of the fuse link between the bosses 29 and 30.

In the form of the invention shown in Figure 4, the transformer terminal is indicated at 31 and the line terminal at 32. An arm 33 corresponding to the arm 39 extends outwardly and carries the adjustable upper electrode 34 corresponding to the electrode 10 of the spark gap, of the first form of the invention.

This construction may be provided with an upstanding portion 35 to which the line wire, not shown, may be connected. It is also provided with a laterally projecting lug 36 to which is bolted a relatively rigid bar 37 and springs 38.

and 39 located on opposite sides of the bar. The bar 37 is provided with a recessed portion 40 which receives the pivot pin 41 carried between a pair of lugs 42 integral with the end or terminal 43 of the fuse tube 44. The spring 38 extends outwardly beyond the portion 40 of the bar 37 and is provided with an outwardly turned outer end 45. It is to be noted that the bar 37 terminates in an outwardly turned end 46. The spring 39 is spaced outwardly from the bar 37 for the majority of its length and has a flat portion bearing against the button 47 of the fuse link 48 and thereby connecting the terminal 32 directly with the fuse link.

The transformer terminal 31 carries a clamping bracket 49 which is provided with an outwardly projecting threaded pin 50 receiving the clamping nut 51 by means of which the leader from the fuse link 48 is clamped.

It is to be noted that the pivot pin 41 of the fuse tube is offset with respect to the point at which the spring 38 exerts its pressure. Consequently there is a tendency of the fuse tube to pivot about the pivot pin 41 in a clockwise direction, and when the fuse link is ruptured, the tube is quickly moved in a clockwise direction, thus withdrawing any remaining unburned portion of the fuse link and actually mechanically moving the end of the fuse tube to a greater distance away from the terminal 31 of the transformer.

It is intended that means, not shown, be provided whereby the terminal 35 may be disconnected from the high tension line. A connecting wire from the terminal 35 may be provided with a hot line clamp, a well known construction and not shown in the drawings, so that the connecting wire may be detached from the line prior to refusing of the device. The fuse tube may be then grasped by the operator and removed from the pivot support 40 of the bar 37, for when the pivot pin 41 is pulled directly outwardly, the spring 38 will yield sufficiently to allow the pivot pin to pass. Thereafter a new fuse link is placed in the fuse tube and the tube repositioned by passing the pin 41 between the spring 38 and the out-turned portion 46 of the bar 37, the spring again yielding and allowing the pin to go into place. The end of the fuse may then be clamped by the thumb nut 51 and the hot line clamp repositioned. Obviously if desired the device could be refused without removing the device from the pivot support 40.

It is apparent that a closed end fuse tube could be employed with the rest of the structure shown in Figure 4. For example, the end 43 of the fuse tube could be provided with a screw cap, as in Figure 3 for instance, and the spring 38 could engage this screw cap.

In the form of the invention shown in Figure 5 the transformer bushing is indicated at 52 and the terminal portion from the transformer is provided with a terminal arm 53 that projects laterally outwardly and upwardly. A second insulator 54 is provided above the bushing 52 and carries the terminal 55 which is connected to the line. The transformer terminal arm 53 may be provided with the link clamping and throwout mechanism similar to that shown in Figure 3, and as in Figure 3, including the movable spring urged member 24' provided with the ears 28' and pivotally supported in the stationary portion 29'. The stationary portion 29' may be integral or may be attached to the arm 53 as desired. The fuse tube 12' may be provided with the clamping

members 16' and 19', as in Figure 3. The device shown in Figure 5 may be refused in exactly the same manner as that described in connection with Figure 3.

It is obvious that the parts may be reversed from that shown in Figure 5. This reversal of parts is shown in Figure 7. In this figure, the transformer bushing is indicated at 52 and the upper insulator at 54. An outwardly and upwardly projecting arm 57 is secured to the transformer terminal 58 and the upper end of the arm 57 is provided with a pin 59 to which the fuse is removably clamped, as previously described, by means of the clamping portions 60 and 61, the fuse tube being indicated by the reference character 62. The fuse link extracting and throw-out mechanism is supported from the upper end of the insulator 54 and is connected to the line wire by any suitable means, as by means of the connector 63. The throw-out mechanism has its stationary portion indicated at 64 and the spring urged movable portion at 65, the ears between which the fuse link passes being indicated at 66. The device shown in Figure 7 may be refused in exactly the same manner as that described in connection with Figure 3.

It is obvious that the form of the invention shown in Figure 4 could be applied in the same general manner as that illustrated in Figure 5. This has been shown in Figure 6.

The arm 53' corresponding to the arm 53 of Figure 5 is provided with a thumb nut 51' which clamps the leader 68' of the fuse link extending from the tube 64'. This tube may be mounted in the same manner as in Figure 4. The terminal member 55 is provided with a connector 56 which receives the conductor from the line wire. As described in connection with Figure 4, it is preferable to provide a hot line clamp for the connecting wire from the terminal 55 so that the device may be refused in the manner described for Figure 4. The terminal 55 is supported from an insulator 54' which corresponds to the insulator 54 of Figure 5.

It will be seen that in all forms of the invention mechanical means are provided for increasing the separation of different parts of the circuit, in addition to the rupturing of the fuse link, so that there is no chance of carbonizing or burning the fuse tube after the fuse link has been ruptured, as sometimes happens when the fuse is not mechanically disconnected, at least at one end thereof, as in the present form of the invention.

It will be seen further that the device is very simple, that the discharge of gases is in a horizontal plane above the top of the transformer casing and consequently during refusing if the fuse blows, the projected incandescent gases and metallic vapors are not adjacent the lineman and greater protection is thereby afforded the lineman if the overload continues during refusing.

It is to be noted further that the position of the parts, either of the lever 24 of Figure 3 or 24' of Figure 5 or of the fuse tube 44 of Figure 4 or 44' of Figure 6, will give a clear indication of a blown fuse and may be readily detected by a lineman.

Although this invention has been described in considerable detail, it is to be understood that such description is intended as illustrative rather than limiting, as the invention may be variously embodied and is to be interpreted as claimed.

I claim:

1. A fuse construction comprising a support, 75

a fuse unit mounted horizontally above said support in a plane spaced from said support, a pair of terminals normally electrically connected by said fuse unit and supported from said support, said fuse unit including a stationary fuse tube, and a fuse link in said fuse tube, one of said terminals having fuse link extracting means electrically connected to said fuse link and biased towards fuse link extracting motion.

10 2. A fuse construction comprising a support, a fuse unit mounted in a substantially horizontal plane spaced from said support, a pair of terminals normally electrically connected by said fuse unit and supported from said support, said fuse unit including a stationary fuse tube, and a fuse link in said fuse tube, one of said terminals having fuse link gripping and extracting means normally gripping said fuse link and yieldingly urged towards fuse link extracting position.

15 3. A fuse construction comprising a support, a fuse unit mounted in a substantially horizontal plane spaced from said support, a pair of terminals normally electrically connected by said fuse unit and supported from said support, said fuse unit including a stationary fuse tube, and a fuse link in said fuse tube, one of said terminals having fuse link gripping and extracting means normally gripping said fuse link and yieldingly urged towards fuse link extracting position, said fuse link gripping and extracting means releasing said fuse link after said fuse link has been extracted.

20 4. A fuse construction comprising a support, a fuse unit mounted in a substantially horizontal plane spaced from said support, a pair of terminals normally electrically connected by said fuse unit and supported from said support, said fuse unit including a stationary fuse tube, and a fuse link in said fuse tube, one of said terminals having fuse link gripping and extracting means normally gripping said fuse link and yieldingly urged towards fuse link extracting position, said fuse unit being detachably related to said support.

25 5. A fuse construction comprising a support, a pair of terminals supported from said support, a fuse unit including a fuse tube having an open end and a fuse link therein and projecting from the open end of said fuse tube, one of said terminals mechanically directly supporting said fuse tube, and a fuse link gripping and extracting means mechanically supported from the other of said terminals and engaging said fuse link for extracting said fuse link, said fuse link gripping and extracting means being free of connection with said fuse tube.

30 6. A fuse construction comprising a support, a pair of terminals supported from said support, a fuse unit including a fuse tube and a fuse link therein, one of said terminals mechanically supporting said fuse tube, and a fuse link gripping and extracting means mechanically supported from the other of said terminals and engaging said fuse link for extracting said fuse link, said fuse link gripping and extracting means being free of connection with said fuse tube, said fuse link gripping and extracting means releasing said fuse link after said fuse link gripping and extracting means has operated to extract any remaining portion of the fuse link after said fuse link has blown.

35 7. A fuse construction comprising a support, a pair of terminals supported from said support, a fuse unit including a fuse tube and a fuse link therein, one of said terminals mechanically supporting said fuse tube, and a fuse link gripping

and extracting means mechanically supported from the other of said terminals and engaging said fuse link for extracting said fuse link, said fuse link gripping and extracting means being free of connection with said fuse tube, said fuse link gripping and extracting means including means for temporarily gripping said fuse link and a horizontally movable spring urged lever for extracting any remaining portion of said fuse link when said fuse link has blown.

8. A fuse construction comprising a support, a pair of terminals supported from said support, a horizontally mounted fuse tube, a fuse link within said fuse tube, supporting means for detachably supporting said fuse tube from one of said terminals, and fuse link extracting means mechanically distinct and separate from said fuse tube carried by the other of said terminals, said fuse link extracting means being free of connection with said fuse tube.

9. A fuse construction comprising a support, a pair of laterally spaced terminals projecting upwardly from said support, an expulsion fuse tube having at least one open end, means for supporting said expulsion fuse tube from one of said terminals, a fuse link carried within said fuse tube and projecting from the open end thereof, and fuse link gripping and extracting means carried by the other of said terminals and including a pivotally mounted spring urged fuse link extracting lever, a portion of the gripping means being carried by said lever.

10. A fuse construction comprising a support, a pair of terminals supported from said support, a fuse tube pivotally supported from one of said terminals, fuse link receiving means carried by the other of said terminals, a fuse link extending through said fuse tube and to said fuse link receiving means, and means urging said fuse tube for rotation in a horizontal plane, said fuse link normally directly restraining rotation of said fuse tube.

11. A fuse construction comprising a support, a pair of terminals supported from said support, a fuse tube pivotally supported from one of said terminals, fuse link receiving means carried by the other of said terminals, a fuse link extending through said fuse tube and to said fuse link receiving means, and spring means binding against said fuse link and urging said fuse tube for rotation in a horizontal plane, rotation of said fuse tube being normally directly restrained by said fuse link.

12. A fuse construction comprising a support, a pair of terminals supported from said support, a fuse tube pivotally supported from one of said terminals and mounted to swing in a horizontal plane, said fuse tube having an open end normally located adjacent the other of said terminals, a headed fuse link extending through said fuse tube and out of the open end thereof and attached to the other of said terminals and normally directly restraining rotation of said fuse tube, and spring means urging said fuse tube towards rotation in a horizontal plane, said spring means bearing against the head of said fuse link.

13. A fuse construction comprising a support, a pair of laterally spaced terminals projecting upwardly from said support, one of said terminals having pivot means, a fuse tube having a projecting portion provided with a pivot pin detachably received by said pivot means, a spring for preventing inadvertent detachment of said pivot pin from said pivot means, said fuse tube

being adapted to swing in a horizontal plane and having an open end normally located adjacent the other of said terminals, the other of said terminals having fuse link receiving means, a fuse link carried within said fuse tube and projecting outwardly through the open end thereof to said fuse link receiving means, and spring means urging said fuse tube towards horizontal swinging motion, said fuse tube being normally restrained against swinging motion by said fuse link.

14. A fuse construction comprising a support, a pair of terminals supported from said support, one of said terminals having a projecting, substantially rigid member provided with a recessed portion adapted to receive a pivot pin and having a spring normally approximately closing the pivot pin receiving portion, a fuse tube having a pivot pin detachably positioned within the pivot pin receiving portion and having an open end normally located adjacent the other of said terminals, a fuse link within said fuse tube projecting outwardly through the open end thereof and extending to and secured to said last mentioned terminal, and a spring urging said fuse tube towards horizontal swinging motion, said fuse link normally restraining the swinging motion of said fuse tube.

15. A fuse construction comprising a support, a pair of terminals supported therefrom, one of said terminals having fuse link receiving means, a horizontally mounted fuse tube having a contact at one end provided with an aperture therethrough and having its other end open and normally located adjacent said fuse link receiving means, a headed fuse link extending through said fuse tube with the head of said fuse link located exteriorly of the contact of said fuse tube and having one end of said fuse link projecting from the open end of said fuse tube and clamped by said fuse link receiving means, the contact of said fuse tube having a laterally projecting arm provided with a pivot pin, the other of said terminals having a substantially rigid member provided with a recessed portion detachably receiving the said pivot pin, a spring for substantially closing said recessed portion to prevent inadvertent detachment of the pivot pin, and a second spring bearing against the head of said fuse link and urging said fuse tube towards horizontal swinging motion.

16. A fuse construction comprising a support having a pair of upwardly projecting terminals constituting a first terminal and a second terminal, a horizontal fuse tube mechanically supported from said first terminal, and having an open end, said fuse tube being mechanically held in a horizontal position after the fuse link has blown, a fuse link normally connecting said terminals and located within said fuse tube and projecting from the open end of said fuse tube, fuse link receiving and clamping means supported from said second terminal and mechanically separate and distinct from said fuse tube, and means for causing relative movement between said fuse tube and said fuse link receiving and clamping means.

17. A fuse construction comprising a support, a pair of vertically spaced terminals projecting upwardly from said support, an expulsion fuse tube having at least one open end, means for supporting said expulsion fuse tube from one of said terminals, a fuse link carried within said fuse tube and projecting from the open end thereof, and fuse link gripping and extracting

means carried by the other of said terminals and including a pivotally mounted spring urged fuse link extracting lever, a portion of the gripping means being carried by said lever.

18. A fuse construction comprising a support, a pair of vertically spaced terminals supported from said support, a fuse tube pivotally supported from one of said terminals, a fuse link receiving

means carried by the other of said terminals, a fuse link extending through said fuse tube to said fuse link receiving means, and means urging said fuse tube for rotation in a horizontal plane, said fuse link normally directly restraining rotation of said fuse tube.

ALWIN G. STEINMAYER.
